[57] **CLAIM**

The ornamental design for an air blowing mirror drier, as shown and described.

DESCRIPTION

FIG. 1 is a front plan view of a air blowing mirror drier showing my new design;

FIG. 2 is a rear plan view thereof;

FIG. 3 is a right side view thereof;

FIG. 4 is a left side view thereof;

FIG. 5 is a top view thereof; and,

FIG. 6 is a bottom view thereof.

The broken line showing of the mirror in FIGS. 3 and 4 is for illustrative purposes only and forms no part of the claimed design.
